UNITED STATES PATENT OFFICE.

WALTER E. BLAINE, OF DETROIT, MICHIGAN, ASSIGNOR TO PACKARD MOTOR CAR COMPANY, OF DETROIT, MICHIGAN, A CORPORATION OF MICHIGAN.

HYDROCARBON-MOTOR.

1,304,733.

Specification of Letters Patent. Patented May 27, 1919.

Application filed September 10, 1917. Serial No. 190,604.

To all whom it may concern:

Be it known that I, WALTER E. BLAINE, a citizen of the United States, and residing at Detroit, Wayne county, State of Michigan, have invented certain new and useful Improvements in Hydrocarbon-Motors, of which the following is a specification.

This invention relates to hydrocarbon motors and more particularly to means for 10 cleaning the air supplied to the motor.

The principal objects of the invention are to provide a device which will efficiently remove the matter in suspension from the air and yet not be cumbersome or too large for 15 attachment to the motor of a vehicle; to provide a device which is of such small dimensions that it can be located close to the motor and carbureter and wholly within the bonnet of the motor vehicle covering the engine; to 20 provide a device which has no moving parts and consequently requires no attention; to provide a simple means for collecting the matter separated from the air; to provide a means for regulating the air pressure in the 25 float chamber of the carbureter in accordance with the air pressure in the cleaning device; to provide a device which is adapted for connection to all the air inlets of the motor carbureter; and to provide an air 30 cleaning device which offers no resistance to the flow of air therethrough and consequently does not affect the efficiency of the motor. Other objects and features of the invention will be apparent from the description 35 taken in connection with the drawings, in which:—

Figure 1 is a plan view of a portion of a motor vehicle showing the bonnet with a part broken away to disclose the motor and 40 the air cleaning attachment as applied to the motor;

Fig. 2 is an elevation of the parts shown in Fig. 1;

Fig. 3 is a sectional elevation through the 45 cleaning device taken substantially on the line 3—3 of Fig. 1, the upper portion of the coil being broken away;

Fig. 4 is a plan view of a carbureter and an end portion of the cleaning device showing 50 the connections to the main and auxiliary air inlets of the carbureter, the conduit from the carbureter to the engine being shown in section; and

Fig. 5 is a perspective view of the air 55 cleaning device.

Referring to the drawings, the reference character A indicates the usual bonnet of a motor vehicle, part of which is broken away in order to show the engine and the arrangement of the air cleaning device. The engine 60 B may be provided with a carbureter C of any desired type and has connected thereto the air cleaning device D, which is located under the bonnet.

As shown in the drawings, the air cleaning 65 device comprises a coil of pipe 10 having an inlet end 11 and a discharge end 12. The form of carbureter shown in the drawings has a main air inlet 13 and an auxiliary air inlet 14. The outlet 12 of the air cleaning 70 device is adapted to be connected with the main air inlet by means of the conduit 15 and the device is also provided with an outlet 16 which is adapted for connection with the auxiliary air inlet 14. Thus as the motor 75 operates, air is drawn in through the air cleaning inlet 11 and supplied to the main and auxiliary air inlets of the carbureter, as required. In passing through the air cleaning attachment, the air travels in a helical 80 path and therefore has given to it a whirling motion which causes matter in suspension to be thrown outward. In order to remove and collect this matter the turns of the coil of pipe are each formed with similarly ar- 85 ranged apertures 17, which register with corresponding apertures 18 in the cover 19 of a receptacle 20. The coil of pipe may be secured to this cover by means of the lugs 21 and bolts 22. As shown in Fig. 3, the recep- 90

tacle may be partially filled with a liquid, preferably an oil, and between adjacent apertures 18 is a partition 23 which is attached to the cover by means such as bolts 24, the partitions extending downwardly and projecting into the liquid so that a series of compartments is formed between the partitions and the cover and top surface of the liquid. Thus each turn of the coil of pipe has a connection through the aperture 17 with one of these compartments, and as the compartments are separated air cannot pass out through an aperture 17, of one turn of the coil, and back through an aperture of another turn. As shown in Figs. 1 and 2, the inlet 11 of the device may be connected with a stove 25 by means of a conduit 26, the stove being provided to heat the air supplied to the motor so that a better vaporization of the motive fluid will be obtained.

In the operation of the device the air supplied to the motor is drawn through the stove 25, thus heating it and carrying it to the inlet 11 of the cleaning attachment. In 5 passing through the device D the air travels in a helical path and is given a whirling motion which throws the matter in suspension to the outer wall of the coil, whereupon it passes through the aperture 17 and into 10 the receptacle 20. Thus the matter in suspension in the air supplied to the motor is removed and collected. In order to equalize the air pressure in the float chamber 27 of the carbureter and the cleaning attachment, a pipe 28 is arranged to connect the 15 last turn of the coil and the float chamber of the carbureter. Thus if the air pressure on the intake side of the carbureter is reduced, the pressure in the float chamber will be 20 brought to the same amount because of the connection 28, and consequently an amount of motive fluid in proportion to the amount of air fed will be forced through the inlet valve of the carbureter. It will be obvious that 25 if the connection 28 were not provided, too much motive fluid would be forced through the needle valve at times when the pressure on the inlet side of the carbureter was reduced. 30 In designing the cleaning attachment according to this invention, the cross sectional area of the turns in the coil of pipe should be such that the air passing through the coil will have sufficient velocity to generate a 35 centrifugal force which will cause the matter in suspension to be thrown outward. On the other hand, the size of the coil is not so small that any substantial resistance will be offered to the flow of the air therethrough. 40 From the foregoing it will be apparent that the means for separating matter in suspension from the air supplied to the motor is exceedingly simple, has no moving parts and therefore requires practically no attention. Furthermore, the attachment is small 45 and it may be located beside the engine and under the usual bonnet of the motor vehicle. Although a specific arrangement and type of device has been described, it is apparent that the form and details thereof may be 50 varied to a considerable extent without departing from the spirit of the invention.

Having thus described my invention, what

I claim as new and desire to secure by Letters Patent is:— 55

1. The combination with the carbureter of a hydrocarbon engine having a float chamber, of means for separating the matter in suspension from the air supplied to the carbureter, and means for maintaining the air 60 pressure in the float chamber substantially the same as in said separating means.

2. The combination with the carbureter of a hydrocarbon engine having a float chamber, of means for separating the matter in suspension from the air supplied to the carbureter and a pressure equalizing pipe connecting the float chamber and said separating means. 65

3. A hydrocarbon motor attachment for 70 cleaning the air supplied to the motor comprising a coil of pipe, a plurality of the turns of the coil each having an aperture through the wall thereof, a receptacle secured to the coil having corresponding apertures, and a partition in the receptacle 75 between adjacent apertures.

4. A hydrocarbon motor attachment for cleaning the air supplied to the motor comprising a coil of pipe, a plurality of the 80 turns of the coil each having an aperture through the wall thereof, a dust collecting receptacle arranged to receive the matter discharged through said apertures and means forming a separate compartment in 85 the receptacle for each aperture.

5. A hydrocarbon motor attachment for 90 cleaning the air supplied to the motor comprising a coil of pipe having an inlet at one end and two outlets at the other, a receptacle secured to said coil, each turn of the coil having an aperture communicating with the interior of the receptacle and means including a liquid forming a separate compartment for each aperture. 95

6. A hydrocarbon motor attachment for 100 cleaning the air supplied to the motor comprising a coil of pipe the adjacent turns of which are in contact with each other and of uniform cross sectional area, a receptacle disposed below said coil and secured thereto, said coil having apertures communicating with the interior of the receptacle and means within the receptacle forming a separate compartment for each aperture.

WALTER E. BLAINE.
